UNITED STATES PATENT OFFICE.

CHARLES MARTIN, OF PARIS, FRANCE.

SMOKE-CONSUMING ATTACHMENT FOR LAMP AND OTHER CHIMNEYS.

SPECIFICATION forming part of Letters Patent No. 312,368, dated February 17, 1885.

Application filed September 29, 1884. (No model.)

To all whom it may concern:

Be it known that I, CHARLES MARTIN, of Paris, in the Republic of France, have invented certain new and useful Improvements 5 in Smoke-Consuming Attachments for Lamp and other Chimneys, of which the following is a specification.

My invention refers to improvements in smoke-consuming attachments for lamp and 10 other chimneys; and it consists of an attachment located at the top of a chimney and provided with a deflector having a central opening placed a short distance above the chimney, a second reflector above the latter, and 15 carrying a bulb-shaped cap having perforated diaphragms at the top and bottom. An interior funnel-shaped shell forms with the cap an annular pocket, which is filled with a suitable absorbent for the products of combustion.

20 The invention consists, secondly, in means for suspending the shade from the chimney, as will more fully appear hereinafter.

In the accompanying drawings, Figure 1 is a side elevation of the attachment as applied 25 to a lamp-chimney; Fig. 2, a vertical central section; Fig. 3, a horizontal section on line *x*, Fig. 1, and Fig. 4 a horizontal section on line *z z*, Fig. 2.

Similar letters of reference indicate corresponding parts.

30 *G* is a chimney or glass cylinder of an ordinary lamp; *B*, a metallic sleeve, which is tightly applied to the upper end of the same; *L*, a bracket projecting from the sleeve *B* and supporting a lever, *D*, the inner end, *D'*, of which is forked.

35 *A* is the lamp-shade; *C*, chains by which the shade *A* is suspended from the forked ends *D'* of the lever *D*, which is retained by friction with the bracket or other means in any 40 desired position. The lamp-shade *A* is suspended free without touching the chimney, and may be placed higher or lower by means of the lever. The sleeve *B* also supports a smoke consuming attachment vertically above 45 the chimney, which consists of a deflector, *H*, having a central opening the area of which should not be more than two-thirds the opening of the chimney *G*.

50 *E* is a second larger deflector, that surrounds the deflector *H*, and *F* a bulb-shaped cap extending above and supported by the deflector

55 *E*. At its bottom the cap *F* is provided with a perforated diaphragm, *J*, having holes of about two millimeters diameter. A second diaphragm, *K*, having smaller holes, is located at the top opening of the cap *F*. An interior funnel-shaped shell, *M*, extends inwardly from the lower diaphragm, *J*, and forms, with the bulb-shaped cap, an annular 60 pocket, *i*, which pocket is filled with a mixture of lime and broken pumice-stone or other suitable absorbent for the gases of combustion. By the arrangement of the perforated diaphragm in the cap the draft is diminished, 65 whereby the unburned particles are forced back into the flame, so as to be more completely consumed, while the products of combustion that pass through the lower diaphragm are retained in the bulb-shaped cap and absorbed by the mixture in the pocket *i*. The 70 smoke-consuming attachment may also be used on a larger scale for the chimneys of any kind of furnaces. It may be made of metal or clay or both combined, and serves to consume the smoke and neutralize the smells, and effects also a considerable saving in fuel by the more perfect combustion taking place in the chimney.

Having thus described my invention, I claim 80 as new and desire to secure by Letters Patent—

1. The combination, with a lamp or other chimney, *G*, of a supporting-sleeve, *B*, deflectors *H* and *E*, a bulb-shaped cap, *F*, perforated diaphragms *J* and *K*, and an interior funnel-shaped shell, *M*, forming a pocket, *i*, filled with absorbent material, substantially as specified.

2. In a smoke-consuming attachment for lamp and other chimneys, the combination, with the chimney *G*, of a sleeve, *B*, deflectors *H* and *E*, and a bulb-shaped cap, *F*, having perforated diaphragms *J* and *K*, substantially as set forth.

3. The combination of a lamp-chimney, *G*, a supporting-sleeve, *B*, bracket *L*, forked lever *D*, *D'*, suspension-chains *C*, and a shade, *A*, substantially as and for the purpose specified.

In testimony that I claim the foregoing as my invention I have signed my name in presence of two subscribing witnesses.

CH. MARTIN.
